HANDLE FOR REFRIGERATED CABINETS

Clare H. Kafer, Palmyra, Mich., assignor to
Revco, Inc., Deerfield, Mich.

Application June 30, 1951, Serial No. 15,730

Term of patent 14 years

(Cl. D67—3)

To all whom it may concern:

Be it known that I, Clare H. Kafer, a citizen of the United States residing at Palmyra, in the county of Lenawee and State of Michigan, have invented a new, original, and ornamental Design for a Handle for Refrigerated Cabinets, of which the following is a specification, reference being made to the accompanying drawing, forming a part thereof.

Fig. 1 is a perspective view on a reduced scale of a handle for refrigerated cabinets embodying my new design;

Fig. 2 is a front elevation thereof;

Fig. 3 is a bottom elevation;

Fig. 4 is a view taken from either end;

Fig. 5 is a section on the line 5—5 of Fig. 2; and

Fig. 6 is an enlarged section taken on the line 6—6 of Fig. 2.

The broken line showing of a cabinet to which the handle is attached is for illustrative purposes only.

I claim:

The ornamental design for a handle for refrigerated cabinets, as shown and described.

CLARE H. KAFER.
